UNITED STATES PATENT OFFICE.

WILLIAM M. WHEILDON, OF ASHLAND, MASSACHUSETTS, ASSIGNOR TO EDWARD H. ANGIER, OF FRAMINGHAM, MASSACHUSETTS.

WRAPPING MACHINE.

Application filed January 14, 1921. Serial No. 437,175.

To all whom it may concern:

Be it known that I, WILLIAM M. WHEILDON, a citizen of the United States, and resident of Ashland, county of Middlesex and 5 State of Massachusetts, have invented an Improvement in Wrapping Machines, of which the following description, in connection with the accompanying drawings, is a specification, like characters on the drawings representing like parts.

This invention relates to wrapping machines and more particularly to that type adapted to enclose an article in a helical winding of paper strip. Such machines 15 are commonly used in wrapping annuli and particularly tires. The object of the invention is the provision of certain improvements in the means for supporting and holding the article to be wrapped to facilitate the making of a satisfactory package.

While my invention may be embodied in various mechanical forms the principles of the same may be well understood by reference to the following description of one 25 particular form shown by way of example in the accompanying drawings, wherein:

Fig. 1 is a side elevation of a tire wrapping machine with parts broken away;

Fig. 2 is an end view seen from the right 30 of Fig. 1;

Fig. 3 is an elevation on an enlarged scale of certain parts; and

Fig. 4 is a central vertical section through what is shown in Fig. 3.

35 The machine shown in the drawings embodies various features of construction not novel to the present application and in particular certain features described and claimed in the patent to Fisher 1,265,640, dated May 7, 1918. As shown in the drawings the machine has a frame comprising an elevated bed 3 beneath which may be housed certain parts of the operating mechanism, from which bed rises a standard 5 in 40 the form of an incomplete annulus gapped at the top on which may be mounted supporting rolls 7 (see Fig. 2). The rolls receive and support for rotation about a horizontal axis the wrapping shuttle 9 in 45 which receives the roll of wrapping material. To rotate the shuttle it may be received in a loop of the driving belt 11 trained about the terminal rolls 7 and the drive wheel 13 carried by the drive shaft 50 55 which is received beneath the bed 3. The

annular article T, usually a tire, is preferably as shown in Fig. 1 supported in vertical position with the lower portion thereof traversing the eye of the shuttle and for this purpose it may be sustained from beneath by two supporting rolls 17 mounted at either end of the shuttle and above the lower run thereof, against which rolls it is held by a guiding follower conveniently in the form of a roll 19 bearing on the upper portion of the tire. Conveniently this roll is pivoted as shown to a post 21 rising from the standard 5 and thus its weight is effective to hold the tire in position and firmly to press it against the rolls 17, one or both 60 of which may be driven to revolve the tire 65 to provide a proper pitch for the wrapping as is common in machines of this type. Referring to Fig. 1 the rotation of the tire in the machine shown is clockwise and the rotation of the left hand roll 17 counterclockwise and the rotation of this roll thus has a tendency to lift the tire. The roll 19 is 70 preferably so pivoted as to tend to swing toward this roll 17 directly to press the tire 75 against the same and resist this lifting tendency.

To center the tire in the wrapping shuttle 9 and to accommodate tires of different diameters the rolls 17 are arranged to move 80 transversely of the plane of the shuttle and suitable means may be provided for giving them simultaneous movements of separation or approach as described in said patent to Fisher above referred to. I have 85 herein illustrated an operating lever 23 for effecting this adjusting movement.

Recent developments in tire wrapping machines have permitted a considerable increase in the speed of the wrapping operation, this being particularly true when packages are formed as described in Patent No. 1,282,167, granted October 22, 1918, to Edward H. Angier. The machines are adapted to wrap tires of varying size both in 90 overall dimension and in cross section. As shown in Fig. 2 the supporting rolls 17 are 95 preferably concaved and are adapted to receive tires of larger sectional form. Tires of comparatively small cross section rest 100 comparatively freely in the concavity of these rolls. It has been found that in wrapping tires at high speed with material capable of exerting a strong tension without 105 breakage, as, for example, in making the 110

package as described in the Angier patent referred to, that the smaller tires are drawn and whipped about laterally to a considerable extent by the tension of the paper. In 5 a machine of the Fisher type as here described this effect is minimized because the wrapping takes place between two rolls 17 disposed at opposite ends of the comparatively small arc of the tire. Furthermore, 10 in a construction as shown wherein the guiding follower 19 exerts its principal pressure in opposition to that of roll 17 which normally tends to lift the tire as illustrated in Fig. 1, the tire is quite firmly pressed 15 against the supporting roll 17. However, small tires at high speeds are capable of shifting on the surface of the supporting rolls 17 and even of bending and twisting laterally between the two points of support 20 provided by these rolls. In accordance with the present invention, therefore, I provide means for laterally supporting the tire substantially at the point of wrapping and in the form shown these means are so provided 25 as to be automatically adaptable to the various sizes of tires which are used in the machine, this being facilitated in particular by the construction of the machine as already described.

30 Referring to the drawings, I provide substantially in the plane of the wrapping shuttle 9 a guide of generally V-shaped form adapted to underride the tire and herein consisting of a pair of diverging rollers 25 35 between which the tire fits, as best shown in Fig. 2. The construction is such that the tire when inserted in the machine rolls into the open side of the V and comes to rest between the sides thereof, the guide automatically adapting itself to the size of the tire. The diverging relation of the rollers 25 permits the accommodation of tires of 40 different sizes. The tire is substantially centered in the shuttle 9 whatever its size, 45 this being made possible by the adjustment of the rolls 17 as in the manner described in the Fisher patent above referred to. The variation in position of the lateral supports which must be provided for to accommodate 50 tires of various cross sections is consequently minimized. On the other hand, the point C, referring to Fig. 2, representing the substantial center of the cross section of the tire, should be fixed and should not be 55 arranged by the lateral supporting means provided by the rollers 25. In the present instance the V-shaped support is yieldably mounted automatically to adjust itself beneath the weight of the tire. I have herein 60 shown on the housing 5 a guideway 27 adapted to receive a slide 29 (see Figs. 3 and 4), on which are mounted the two rollers 25. Yieldably to support the slide 29 I have provided the spring 31, conveniently 65 a spiral coil spring analogous to a watch

spring since this form permits a relatively wide variation of movement with substantially constant resistance. The function of the spring is simply to provide a counter-balancing support for the slide 29 and does 70 not exert any substantial pressure through the rollers 25 on the tire T. On the contrary, the weight of the tire freely displaces the rolls and these provide merely a lateral support therefor during the wrapping operation. As shown the rollers 25 may lie substantially in the plane of the shuttle closely adjacent and preferably somewhat in advance of the point of application of the wrap. 75

80 Referring to Fig. 1, it will be seen that the guiding rollers 23 are closely adjacent to the left hand traction roll 17 in that figure which draws the tire through the shuttle and are in advance thereof. I have 85 found that guiding rollers in this location serve to center the tire in the concavity of the supporting roll even although they exert substantially no pressure on the tire itself. While I do not understand that the action 90 is the same, the effect may be compared by way of analogy to the guiding of a belt on a pulley. It is possible to control and guide a belt from the side which leads to the pulley whereas it cannot be controlled from 95 the side from which it leaves the pulley. Similarly a guide located in the rear of instead of in advance of the traction roll is not effective to center the tire thereon. In the present instance the guides 25 adapt 100 themselves to tires of various sizes automatically as the tire is introduced into the machine. While they need exert no substantial deforming pressure on the tire itself, they may be arranged as shown to take 105 up a certain amount of the pull of the wrapping and in any event they serve to guide and center the tire in the traction roll 17 and aid in making it run true as it revolves.

110 Conveniently the axes of the rolls 25 are inclined so that they are substantially parallel with the pitch of the wrapping as best illustrated in Fig. 1, and the axis may be such that if extended it would come close to the mean position of follower roll 19. In other 115 words, the roll 19 may swing substantially in a plane defined by the axes of the two rolls 25. This arrangement provides for the most effectual resistance to the upward and sideways pull of the wrapping. 120

Claims:

1. In a wrapping machine of the class described comprising a wrapping shuttle and rolls at opposite sides thereof for supporting an article in traversing relation thereto, an upwardly opening V-shaped guide receiving the article adjacent the point of application of the wrap and freely displaceable downwardly by the article. 125

2. In a wrapping machine of the class de- 130

scribed comprising a wrapping shuttle and rolls at opposite sides thereof for supporting an article in traversing relation thereto, a member adjacent the shuttle carrying a 5 diverging pair of rollers and yieldably supported to be displaced by a tire entering between the rollers.

3. In a wrapping machine for annuli, a circular shuttle mounted for rotation about 10 a substantially horizontal axis, supporting and driving means for the annulus located at opposite ends of the shuttle above the lower run thereof to sustain the annulus in an upright position in traversing relation 15 to the shuttle for rotation about a substantially horizontal axis, a guiding follower above the shuttle in position to bear down upon the annulus to hold the same upon the supporting means in a substantially up- 20 right position, means for imparting rotative movements to the shuttle, means for driving the supporting means to rotate the annulus and a V-shaped guide located between the supporting means to underride the annulus 25 and yieldable under the weight thereof.

4. In a wrapping machine for annuli, a circular shuttle mounted for rotation about a substantially horizontal axis, supporting and driving means for the annulus located 30 at opposite ends of the shuttle above the lower run thereof to sustain the annulus in an upright position in traversing relation to the shuttle for rotation about a substantially horizontal axis, a guiding follower 35 above the shuttle in position to bear down upon the annulus to hold the same upon the supporting means in a substantially upright position, means for imparting rotative movements to the shuttle, means for driving 40 the supporting means to rotate the annulus, means for causing simultaneous separation or approach of the supporting means to maintain annuli of different sizes with the portion traversing the shuttle substantially 45 central thereto and a V-shaped guide located between the supporting means to un-

deride the annulus and yieldable under the weight thereof.

5. In a wrapping machine of the class described a rotary wrapping shuttle, means 50 for supporting and feeding an article in traversing relation thereto and lateral guides for the article adjacent the point of application of the wrap inclined substantially to parallel the pitch of the wrapping. 55

6. In a wrapping machine for annuli in combination, a circular shuttle to revolve about the annulus, a traction roll to underride the annulus and advance it through the shuttle and a pair of diverging guide mem- 60 bers adapted to receive the annulus between them and yieldably supported to automatically adjust themselves to annuli of different sizes, said members being mounted in advance of but adjacent to said roll to 65 center the annulus thereon.

7. In a wrapping machine for annuli in combination, a circular shuttle to revolve about the annulus, a driven roll adjacent the shuttle engaging the annulus to draw it 70 through the shuttle and a pair of diverging guide members engaging the annulus adjac- 75 ent the point of wrap and closely in ad- vance of said roll to center the annulus thereon, said members being yieldably sup- ported automatically to adjust themselves to annuli of different sizes.

8. In a wrapping machine for annuli in combination, a circular shuttle to revolve about the annulus, a traction roll to under- 80 ride the annulus and advance it through the shuttle and lateral guide means adapted to engage the sides of the annulus and to be positioned thereby without substantial de- forming pressure on the annulus, said 85 means being located in advance of and ad- jacent to the roll to serve as a centering guide for the annulus thereon.

In testimony whereof, I have signed my name to this specification.

WILLIAM M. WHEILDON.
